UNITED STATES PATENT OFFICE.

CHARLES STUART SOMERVELL, OF RIVERTON, NEW JERSEY; BERTHA W. SOMERVELL
ADMINISTRATRIX OF SAID CHARLES STUART SOMERVELL, DECEASED, ASSIGNOR
TO PENNSYLVANIA GASOLINE DRILL COMPANY, OF PHILADELPHIA, PENNSYLVANIA, A CORPORATION OF DELAWARE.

IMPACT OR PERCUSSIVE TOOL OF THE EXPLOSIVE-MOTOR TYPE.

Application filed August 25, 1923. Serial No. 659,350.

My invention relates to a type of drill, hammer or similar impact device in which a unitary piston-hammer is reciprocated within a cylinder to impart a heavy impact to a tool, such as a drill or a drill-bit, or a riveting, or a digging tool or similar tools, the movement of such piston-hammer being derived from the combustion of an explosive mixture under compression in one end of the cylinder.

The structure forming the subject-matter of the present invention includes a cylinder and an impact piston or piston-hammer reciprocating within the cylinder on the principle of a single-acting two-cycle combustion engine in that fuel is drawn into a mixing or transfer chamber on the compression stroke, is initially compressed in the said chamber on the working stroke, is transferred under pressure to the combustion end of the cylinder to expel the products of combustion of the previous working stroke at the end of the working stroke, is compressed in the combustion chamber during the compression stroke, and is exploded at the end of the compression stroke to impel the piston or piston-hammer forwardly to effect the working stroke.

One object of the present invention is to provide a portable, substantially self-contained, easily handled and manually controlled tool of the impact-hammer type, with simple and efficient means whereby the explosive mixture may be drawn into the cylinder, compressed and transferred to the explosion chamber where it is finally compressed and exploded to forcibly impel the piston-hammer at a high speed, for the purpose of imparting a powerful percussive blow to the shank of a drill, chisel, riveting or digging tool, or the like.

A further object of my invention is to provide means for regulating or controlling the force of the impact of the piston-hammer against the tool; to provide a rotor, preferably surrounding the cylinder, for effecting the return or compression stroke of the piston-hammer, and preferably at a substantially constant linear speed; and to rotate said rotor during the automatic operation of the machine at a substantially constant speed of rotation as a result of the engagement therewith of the piston-hammer during the

first part, portion or fraction of the working stroke of the piston-hammer, the energy 55 so stored in the rotor as momentum being sufficient to effect the return or compression stroke of the piston-hammer and maintain a substantial constant speed of rotation to the rotor.

A further object of my invention is to provide a construction wherein the piston-hammer, after moving out of engagement with the rotor, is free to move under the explosive force of the burning fuel, and may 60 be substantially unrestrained during the latter part, half or fraction of its working stroke whereby a heavy sharp, effective blow may be imparted thereby to the tool which it substantially strikes at the end of the working stroke.

A further object of my invention is to provide construction wherein during the latter half, part, portion or fraction of the stroke and up to substantially the moment of the 75 impact of the piston-hammer with the tool, the piston-hammer may be freely impelled at a constantly accelerated linear speed under the explosive action of the ignited fuel, and the linear speed of said piston-hammer 80 may be highest at or about the moment of its impact with the tool.

A further object of my invention is to provide simple and efficient means for compressing and transferring the charge from 85 the intake chamber to the explosion end of the cylinder.

A further object of my invention is to substantially provide within the cylinder three chambers, one being the explosion chamber, wherein the charge is exploded and the force of the explosion is imparted to the piston to effect the working stroke or blow; the second being the intake chamber, into which is drawn the explosive mixture by the upward or non-working stroke of the piston-hammer; and the third being a chamber 90 into which air is drawn during the non-working stroke of the piston-hammer and in which the said air is compressed during the working stroke of the piston-hammer, said compressed air being utilized for several purposes, among which may be (1) the removing of the detritus or dust from the bottom of the hole being drilled; (2) the cooling 100 of the cylinder at the combustion end 105

thereof; (3) the regulation or control of the force of the blow that the piston-hammer imparts to the tool; and (4) the clearing of the air filters or screens. The last of these 5 chambers above referred to will, for convenience, be referred to as the air compression chamber.

A further object of my invention is to prevent dust from entering the air compression chamber and to prevent the accumulation of dust in the filter through which the air may be conducted to the air compression chamber.

A further object of my invention is to 15 provide said air compression chamber with a regulating valve or mechanism whereby the pressure to which the air is compressed in said chamber may be varied and controlled to vary, if desired, the force of the 20 impact-hammer upon the tool, and to prevent any permanent accumulation of dust in the filters or screens through which air is conducted to the air compression chamber.

A further object of my invention is to 25 provide means for rigidly mounting the cross-head pin in the piston-hammer so that said cross-head pin will not become loosened or displaced under the vibration to which the machine is subjected while operating.

30 A further object of my invention is to provide an improved means for keeping constantly lubricated the cam, the cross-head cooperating therewith, and the hammer head, and to prevent the escape of the lubricant from the machine when the machine is inclined from a vertical position.

A further object of my invention is to 40 rigidly mount upon the impact tool, the means for carrying a liquid fuel, the ignition coil and the condenser; and to provide the structure with means whereby a part of the weight of the entire mechanism may be rested upon the leg, thigh or knee of the operator, when the device is being used in a 45 position inclined from the vertical, or is being carried by the operator from place to place.

A further object of my invention is to 50 provide the rotor with two cams, one of which cooperates with the piston-hammer during the operation of the device to receive energy from the piston-hammer during the working stroke and store it in the rotor as momentum and to impart to the 55 piston-hammer its return or compression stroke; the second of which is operative to effect the downward movement of the piston and the transfer of the explosive mixture to the explosion chamber in starting the 60 automatic operation of the mechanism.

A further object of this invention is to 65 so securely and permanently maintain all the parts in their assembled position that they are not liable to move or become disarranged, loosened or displaced under the

violent vibrations to which the machine is subjected while operating.

A further object of my invention is to provide the tool receiving end of the cylinder with a strike-pin or impact receiving member freely movable, within limits, but held in the cylinder against bodily removal, and adapted to transmit the impacts received by it from the piston-hammer, to the shank of the tool, carried by the chuck, and 75 to convey and deliver compressed air to the bore of the tool to remove detritus from the hole being drilled.

A further object of my invention is to 80 provide means to prevent the escape of air around the outside of the shank end of the tool, and compel such compressed air to pass into and through the tool.

Further objects of my invention are to 85 limit the downward movement of the piston-hammer by the engagement of the cross-head pin with the bottoms of the slots through the cylinder, before the rollers of the cross-head reach the lowest portion of the cam of the rotor; to prevent the ends of 90 the cross-head from contact with the lowest part of the cam when a cavity or soft spot is encountered in operating the drill or when the device is being carried from place to place while operating; to provide a construction wherein the ends of the cross-head 95 will not be subjected to any blow or impact whatever at the end of the working stroke of the piston-hammer; and to provide means for absorbing a severe blow of the piston-hammer against the strike-pin, or the parts in which the strike-pin is mounted, when the resistance of the material being drilled is lessened for any reason.

100 Further objects of my invention are to provide means with the drill structure for compressing air, and conducting it to and through the hollow bore of the tool-bit.

A further object of my invention is to divide the cylinder by the piston-hammer into 110 an explosion or combustion chamber located at one end of the cylinder, and two other chambers, one of said other chambers being at the other end of the cylinder and the other being intermediate the piston-end and 115 the hammer-end of the piston-hammer, one of said two chambers being a fuel receiving or mixing chamber, and the other being an air compression chamber.

A further object of my invention is to 120 provide the air compression chamber with a valve to limit the pressure to which the air therein may be compressed, and to provide means for allowing the escape of air from said compression chamber when the 125 pressure therein is above any desired predetermined point.

Further objects of my invention are to divide the interior of the cylinder by the piston-hammer into three chambers or com- 130

parts, one of which is a combustion or explosion chamber located at one end of the cylinder and the other two of which are respectively a fuel intake chamber and an air compression chamber, and to make these three chambers of substantially the same length and with substantially the same clearance for the parts of the piston-hammer coacting therewith, so that substantially all the charge in the mixing chamber is transferred at a relatively high pressure to the combustion chamber at the end of the working stroke, and substantially all the air in the air compression chamber is expelled on each working stroke in a series of puffs or pulsations, each of high pressure.

A further object of my invention is to convey to the bore of a hollow drill a continuous series of puffs or pulsations of compressed air at high pressure to blow dust or detritus from the hole being drilled substantially as fast as it is formed.

Other objects of my invention will appear in the specification and claims below.

In the drawings forming a part of this specification and in which the same reference characters are employed throughout the various views to designate the same parts,

Fig. 1 is, in general, a front vertical sectional view of the complete device, the canis, the chuck, the tool and parts of the piston-hammer being in elevation,—not sectioned;

Fig. 2 is, in general, a vertical sectional view similar to Fig. 1 but taken at right angles to the position shown in Fig. 1, the tank, however, and parts mounted thereon, being shown in side elevational view;

Fig. 3 is a fragmentary plan view of the connection between the supports for the fuel tank and the lower part of the tool;

Fig. 4 is a side elevational view of the cross-head, comprising the cross-head pin and the rollers and collars mounted thereon;

Fig. 5 is a longitudinal vertical sectional view of the cylinder and a portion of the piston therein, taken on line 5—5 of Fig. 7 to show the way in which compressed air from the compression chamber may be conducted to the cylinder-head for cooling purposes and showing, in detail, the manner in which the intermediate cylinder-head is secured in the cylinder;

Fig. 6 is a horizontal sectional view on the line 6—6 of Fig. 5;

Fig. 7 is a horizontal sectional view of the structure shown in Fig. 5, said section being taken just above the intermediate cylinder-head;

Fig. 8 is a detail view of the lower portion of the hub of the rotor with the cam removed therefrom;

Fig. 9 is a development in a horizontal plane of the two cams of the rotor, the circles indicating the relative position of the rollers of the cross-head pin with respect

thereto during the travel of one-half of the entire contour of the cam;

Fig. 10 is a plan view of a portion of the cover showing the contact device of the ignition system and the manner of mounting the same;

Fig. 11 is a diagrammatic view of the ignition system;

Fig. 12 is a plan view, partly in section, of the oil pan and conduits therefrom for the air to and from the compression chamber, the air filtering device being shown in horizontal cross-section and attached to the pan;

Figs. 13 and 14 are detail views showing how the cross-head pin is locked into the piston-hammer to prevent any longitudinal movement thereof therein;

Fig. 15 is a fragmentary sectional view of a modified construction wherein the air from the compression chamber is conducted to the bottom of the strike-pin as distinguished from being conducted directly through the entire length of the strike-pin as exemplified in the construction shown in Figs. 1 and 2;

Fig. 16 is a further modified form of my invention, the drawing being generally a vertical sectional view similar to Fig. 1 but with the piston-hammer in its elevated position; that is to say, at the end of the compression stroke or the beginning of the working stroke.

Referring first to the form of my invention as illustrated particularly in Figs. 1, 2 and 5, I provide a cylinder 1 having therethrough a cylindrical bore of uniform diameter throughout and provided at substantially midway between the ends thereof with a pair of diametrically opposite longitudinal slots 2—2^a extending through the wall of the cylinder. Mounted within said cylinder and smoothly fitting the bore thereof is a piston-hammer 3, adapted to be reciprocated therein somewhat on the principle of a single-acting two-cycle combustion engine, as will be referred to and explained more fully below.

The upper and power end of this cylinder 1 is preferably provided with longitudinally extending radially projecting ribs or fins 4 to provide a large heat-radiating surface around the power end of the cylinder 1. Said power end is closed by a cylinder-head 5 secured thereto preferably by bolts 6 extending through said head 5, and terminating in

T-shaped heads 7 adapted to fit into transverse slots 8 in a pair of adjacent ribs or fins 4. Between the head 5 and the coacting end of the cylinder 1, a suitable gasket 9 (preferably of metal) may be clamped so as to close perfectly the working end of the cylinder. The cylinder-head 5 may be provided with oppositely extending sleeve-like projections 10 into which may be fitted handles 11 for manipulating, controlling and directing the mechanism. The cylinder-head 5 is also preferably provided with a series of general-

ly radially extending ribs or fins 12 to provide a suitable heat-radiating surface therefor. The cylinder-head 5 is also preferably provided with a tapped opening 13 into which may be fitted a spark plug 14. The piston-hammer 3 comprises at one end a working or explosion piston-portion, or piston 15; at the other end a hammer portion, impact member or hammer-head 16, and an intermediate cross-head or portion 17, within which is rigidly mounted a cross-head 18 which will be more fully described below. The working or explosion piston 15 is preferably rigidly and integrally united to said intermediate portion 17 by a substantially cylindrical piston rod 19 and the hammer-head or piston 16 is also preferably rigidly integrally united with the intermediate portion 17 by a connecting portion 20 preferably of considerably smaller diameter than that of the piston-end 15 or the hammer end 16.

Within the bore of the cylinder 1 and close to the piston-head 15, when the latter is at the limit of its forward or downward stroke, (as shown in Fig. 1), I provide an intermediate cylinder-head 21 through which the piston rod 19 passes. This cylinder-head 21 preferably consists of a pair of semi-discs 22—22 (see Figs. 5 and 7) together having an exterior diameter equal to the diameter of the bore of the cylinder and when placed together providing between them a circular hole at the center thereof to fit rather closely around the piston rod 19. They are seated upon the tapered ends 23 (see Figs. 5 and 7) of a plurality of screws 24 radially extending into the bore of the cylinder beneath said members. Upon the disc thus formed is placed an annulus or disc 25 of any suitable packing material, preferably channel-shaped in cross-section and upon the latter are placed two more similar semi-discs 26—26 preferably arranged so that the line of separation between the two latter semi-discs is equally spaced from the line of separation between the two semi-discs 22—22. These semi-discs 26—26 are, however, of smaller diameter than that of the semi-discs 22, and they preferably provide a larger central opening therethrough so that the disc of packing is compressed between the outer periphery of the discs 26 or inner wall of the cylinder; between the two sets of discs; and between the inner wall of the opening through the discs 26 and the piston rod 19. Above this upper set of semi-circular discs 26 are provided a plurality of screws 27 having tapered ends 28 which project through the walls of the cylinder 1 and fit over the upper face of the discs 26. In this way the lower portions 22 of the intermediate cylinder-head 21 are firmly seated on the lower pins or screws 25 and the upper portions 26 are pressed toward said lower portion to compress the packing therebe-

tween. The intermediate cylinder-head 21 is thus held immovable within the bore of the cylinder and any leakage of gas around the periphery thereof or between said head and the rod 19 is prevented. This intermediate cylinder-head 21 is assembled around the piston rod 19 before the same is inserted into the bore of the cylinder and then is slid with the piston-hammer into the bore of the cylinder. One set of screws 24 or 27 is then inserted to form a seat for the head. The other set of screws is then inserted through the wall of the cylinder to engage the other side of the intermediate cylinder-head 21 and thus positively rigidly hold the intermediate cylinder-head 21 in position to compress the packing therebetween and form a tight joint between the bore of the cylinder and the said cylinder-head 21, and between the piston rod 19 and the cylinder head 21. In this form or embodiment of my invention, the space 29 between the piston 15 and the intermediate cylinder-head 21 constitutes the fuel intake and mixing chamber of the device, and the space 30 between the piston 15 and the cylinder-head 5 constitutes the explosion or expansion chamber of the device. On one side of the working end of the cylinder 1, I provide a carburetor 31 which communicates through a passage 32 with the chamber 29. This carburetor is more or less diagrammatically illustrated in Fig. 1 as comprising a valve member 33 normally yieldingly held upon its seat by a spring 34 and having a fuel inlet duct 35 opening into the seat of the valve member 33 and closed by the valve member 33 when the latter is on its seat. The fuel inlet duct 35 is preferably in communication with the reservoir or tank 36 through a small tube or pipe 37. When the piston 15 rises from the position shown in Fig. 1 and moves toward the cylinder-head 5, air is drawn in through the passages 38 at the bottom of the valve 31, lifting the valve 33 off of its seat admitting liquid fuel through the inlet duct 35, which fuel is mixed with and carried by the air into the chamber 29 of the cylinder. In this way an explosive mixture is taken into the space or chamber 29 on the up-stroke of the piston-hammer 3. The position of the piston-hammer at the end of the upward or non-working stroke is shown in Fig. 2.

The cylinder 1 is also provided with a port 39 which by a passage 40 communicates with a port 41 on the other side of the piston 15. When the piston 15 is in its lowest position the chamber 29 is thus put into communication with the chamber 30. The chamber 30 is also preferably provided with an exhaust port 42 which communicates by suitable pipe or conduit 42a with the atmosphere when the piston is at or near the end of its downward or working stroke.

By this arrangement the upward move-

ment of the piston-hammer draws the mixture of air and fuel from the carburetor 31 and port 32 into the chamber 29 below the piston 15. On its downward stroke, the charge thus drawn into the chamber 29 is compressed until the upper end of the piston 15 clears the ports 41 and 42 whereupon the compressed explosive mixture is transferred from the chamber 29 to the chamber 30 at the explosion or working end of the cylinder, this fresh charge being deflected upwardly or toward the cylinder-head 5 by the deflector 43 on the head of the piston 15. This inrush of the fresh charge serves, when the device is in operation, to expel the spent gases remaining in the chamber 30 at the end of the working stroke. After the charge has thus been transferred to the chamber 30 the piston on its upward movement closes both ports 41 and 42 and compresses the charge in the chamber 30 between the piston 15 and the cylinder head 5. At the completion of the upward stroke, the charge is ignited by the spark plug 14 and the piston is impelled downwardly under the explosive force of the burning mixture and the cycle of operation is repeated. Thus it will be apparent that the piston-hammer is reciprocated within the cylinder on the principle of a two-cycle internal combustion engine in so far as the intake, transfer and compression and explosion of the explosive mixture is concerned, and in so far as the expulsion of the spent charge by the incoming fresh charge is concerned. The mechanism whereby the return or non-working stroke of the piston is effected will be described below.

The working piston 15 may be provided with the usual piston rings 44. In order that the piston 15 may have a relatively long bearing surface in the cylinder and yet not be unduly heavy I prefer to make the working piston 15 hollow, as clearly shown in Figs. 1, 2 and 5. In order to render the upper end of the piston sufficiently strong and rigid to withstand the high pressure to which it is subjected by the exploding gases, I prefer to provide the upper end thereof with a hole into which is threaded a stiffening stud 45 the lower end of which is forced hard against the lower wall 46 of the chamber 47 in the piston 15. In this way a relatively light piston may be employed, with the working end thereof sufficiently strong to withstand the heavy pressures and shocks to which it is subjected. To prevent the stud 45 from turning and becoming loose, by reason of the vibration to which all the parts are subjected during the operation of the device, I prefer to lock the stud with a screw or stud 45^a after the stud has been properly positioned in the hole in the piston-head.

The lower ends of the ribs or fins 4 on

the upper end of the cylinder 1 may be and preferably are squared to provide a shoulder 48 and fitting against the shoulder and surrounding the cylinder is a hood or cover 49 having somewhat the form of a shallow inverted bowl. Over the cylinder 1 is then similarly slipped an upper ball race 50 which is adapted to abut squarely against the inside of the hood or cover 49 and to fit snugly against the outer wall 70 on the cylinder 1 at that point. Between this upper ball race 50 and a coacting lower ball race 51 is disposed a series of antifriction balls or rollers 52. Said ball race 51 is securely seated in the upper section 53 of a hub or rotating member 54. The lower section 55 of the member 54 is rigidly secured to the upper section 53 by bolts 56 as clearly shown in Fig. 1. To the inside of the upper section 53 of the hub 54 a cam 57 is secured by bolts or screws 58 (see Fig. 1) and this cam, so attached to the upper section 53 of the hub, is adapted to be slipped over the lower end of the cylinder 1 with the upper hub member 53 to 90 the position shown in Fig. 1 in assembling the device.

The intermediate portion 17 of the piston-hammer 3 is preferably nearly but not quite as large as the diameter of the bore 95 through the cylinder 1 and it is transversely diametrically bored to receive a cross-head pin 18. This cross-head pin 18 (see Fig. 4) is preferably provided with a cylindrical central portion 59 adapted to fit tightly into a cylindrical opening 60 extending transversely through the intermediate portion 17 of the piston-hammer. The central cylindrical portion 59 terminates on one side in a rectangular head 61 adapted to fit into a correspondingly shaped rectangular recess or depression 62 provided at one end of the transverse hole 60 through the portion 17 and adjacent said head 61 said cross-head pin provides two parallel flat vertical faces 63 adapted to smoothly fit into the slot 2^a extending longitudinally of the cylinder. These faces 63 are preferably provided with grooves 64 to facilitate the lubrication thereof. Beyond these flat vertical faces 63 said cross-head pin is provided with a cylindrical portion 65 of reduced diameter and upon which is mounted to turn a hardened steel roller 66 securely held in place by a collar 67 secured to the cross-head pin 18 by a transverse tapered pin 68 driven through the collar 67 and a transverse hole at that end of the cross-head pin 18. The opposite end of the central cylindrical portion 59 of the cross-head pin 18 is similarly provided with a pair of parallel vertically disposed flat faces 69 adapted to fit smoothly between the parallel walls of the slot 2 on the other side of the cylinder 1 and said faces 69 are also preferably provided with oil grooves 130

69^a. Beyond these flat faces 69 said cross-head pin 18 is provided with a reduced cylindrical portion 70 upon which is mounted a hardened steel roller 71 similarly held 5 in place by a collar 72 and a tapered pin 73 driven through said collar 72 and the end of said cross-head pin 18.

The width of the cross-head pin 18 between the parallel faces 63 is not less than 10 the diameter of the cylindrical portion 59, so that, to assemble the device it is only necessary to insert the piston-hammer within the bore of the cylinder and bring the hole 60 in the intermediate portion 17 into alinement 15 with the slots 2 and 2^a whereupon the cross-head pin may be inserted into the said hole 60 through the wide slot 2^a and driven until the shoulder of the rectangular portion 61 fits into the rectangular recess at the end 20 of the hole 60. The cross-head pin 18 is arranged to fit tightly in the opening 60 and keep said pin in proper relation thereto, with the flat faces 63 and 69 parallel to the slots 2^a and 2 respectively. The hole 60 is 25 provided with a keyway 74 and the cross-head 18 with a key 75 slidable in said keyway. This prevents any rotation of the pin 18 within the hole 60 in driving the cross-head into final position therein.

30 On account of the severe vibrations to which the parts are subjected when the drill is being operated, it may be desirable in some instances to further lock the cross-head pin 18 to the piston-hammer and to do so I 35 may provide the cross-head pin 18 with a transverse hole 59^a to receive the end of a screw 76 projecting into the said hole 59^a.

As clearly shown in Figs. 13 and 14 the intermediate portion 17 may be provided 40 with a relatively wide slot 17^a and a hole 17^b tapped to receive the screw 76. A lock plate or washer 17^c fits between shoulders of the slot 17^a and cannot rotate on the screw 76. The washer 17^c has one or more 45 prongs 17^d adapted to be bent up into one or more of the notches 17^e in the head of the screw 76. After the cross-head pin has been driven into the hole 60 of the intermediate portion 17, and its end into the hole 50 or recess 58^a in the cross-head pin 18, as above described, and is tight in its final position, a prong 17^d is bent outwardly into a notch 17^e of the screw head, thus definitely locking the screw and preventing it and the 55 cross-head pin 18 from becoming loose. The cylinder 1 is provided with an opening 1^c into alinement with which the head of the screw 76 may be brought for the passage of a tool to insert or withdraw the screw 76. 60 After the cross-head pin 18 has been thus inserted into the piston-hammer and secured thereto, the lower section 55 of the hub 54, with the lower cam 77 secured therein as by screws 78 threaded into holes 78^a therein, 65 is slipped over the lower end of the cylinder

1 and said lower section 55 is secured to the upper section 53 of the hub by the bolts or screws 56. In the lower end of the lower section 55 of the hub 54 is a recess 79 in which is seated an upper ball race 80 in 70 which a series of antifriction balls or rollers 81 are adapted to track.

The exterior of the cylinder is provided with screw threads 82 over which may be threaded a flanged ring 83 which carries the 75 lower ball race 84 adapted to coact with the under or inner side of the balls 81. When this flange 83 is properly adjusted, the entire hub 54 with the parts attached thereto is adapted to rotate on the balls 81 and 52 so on an axis coincident with the longitudinal axis of the cylinder 1 and the longitudinal axis of the piston-hammer 3.

Beneath the flanged ring 83 and surrounding the cylinder 1 is a friction ring 85, which is preferably of steel, and against this ring 85 bears the inner inside bottom wall 86 of the oil pan or lubricant reservoir 87. The inside wall of the hole through the bottom wall of the oil pan 87 fits snugly against 90 a smooth cylindrical surface 88 on the cylinder 1 immediately below the screw-threads 82 and a short distance below this smooth cylindrical surface 88 is a threaded section 89 of slightly smaller diameter than the diameter of the cylindrical surface 88. A ring 90 of packing material is fitted snugly against the bottom of the oil pan 87 and next to that is placed a nut-lock 91. Next below the nut-lock 91 is a nut 92 adapted to be 100 threaded over the threaded section 89 of the cylinder. After the flanged ring 83 has been adjusted to make a proper bearing for the hub 54 on the balls 52 and 81, the nut 92 is adjusted so as to tightly compress the bottom of the oil pan between the steel ring 85 and the packing ring 90 so as to make a liquid tight closure for the bottom of the oil pan or receptacle around the outside surface of the cylinder 1. The bottom 110 wall of the pan 87 is provided with a series of notches 93 and the upper face of the nut 92 is also provided with a series of similar notches 94. The nut-lock 91 is provided with a series of radially extending fingers or prongs 95 and when the nut 92 has been adjusted in its final position, one or more of these prongs is bent upwardly into the notches 93 on the bottom of the pan and other of these prongs or fingers 95 are bent 115 downwardly to engage with notches 94 in the nut. In this way the nut is positively locked and held in its adjusted position.

The hammer-head 16 is preferably provided with a series of packing rings 96 and 125 is adapted to compress and force air under pressure through the drill-bit to the bottom of the hole being drilled for the purpose of removing dust or detritus therefrom.

The lower end of this cylinder 1 is pro- 130

vided with an anvil 97 closely fitting the interior walls of the cylinder and provided preferably with an enlarged end or head 98 fitting into an annular recess 99 at the end 5 of the cylinder. This anvil 97 is preferably held in position by a tool-chuck or tool-holder 100 which is held firmly against the end of the anvil 97 and the end of the cylinder by bolts 101 passing through ears 102 10 projecting radially therefrom, said bolts also passing through a ring 103. The opening 104 through the ring 103 is preferably slightly larger than the external flange 105 at the end of the cylinder so that the ring 103 15 may be readily passed over said flange. Between said ring 103 and the flange 105 is interposed a split ring 106 fitting against the upper shoulder of the flange 105 and having its upper face 107 inclined and fitted against 20 a correspondingly inclined surface 108 on the ring 103. After passing through the ring 103, the bolts 101 are surrounded by coil springs 109, the compressive force of which may be adjusted by the nuts 110 on 25 the ends of the bolts 101. When so assembled the springs hold the tool-chuck squarely against the end of the cylinder, the head 98 of the anvil 97 against the bottom wall of the recess 99 and the split ring 106 firmly 30 against the outside of the cylinder 1 and against the upper surface of the flange 105.

The anvil 97 is provided with an opening 111 circular in cross-section, extending coaxially therethrough and in this opening is 35 slidingly fitted the strike pin 112. The opening 111 is of larger diameter at its lower end than at its upper end to provide a shoulder 111^a relatively near the lower end of the anvil, and the strike-pin 112 is provided with a flange or head 113 which is 40 adapted to fit against the said shoulder 111^a. The head or flange 113 smoothly fits within the larger end of the opening 111 and the body of the strike-pin smoothly fits within 45 the smaller diameter of the opening 111 through the anvil. The length of the strike-pin is such that when the head or flange 113 is seated against the shoulder 111^a, the upper end of the strike-pin projects slightly 50 above the inner face of the anvil 97 so as to receive the blow delivered by the piston-hammer when the hammer head 16 strikes the upper end of the strike-pin 112.

The extent to which the strike-pin 112 is 55 made to project above the top of the anvil 97 may vary and depends upon the nature of the work for which the device is to be used. Generally speaking, the strike-pin should project above the anvil a distance 60 substantially equal to the greatest distance that the tool will normally advance under a single blow in drilling or cutting a given material, but in drilling rock and other materials, soft spots or cavities are frequently 65 encountered by the drill with the result that

the drill will advance an abnormally great distance under an impact of the hammer. When this occurs, the hammer-head 16 will impinge against the top of the anvil 97 and the blow thereupon will generally be absorbed by the springs 109. 70

In this embodiment of my invention, the strike-pin is provided with a small bore 114 extending longitudinally therethrough for the purpose of delivering compressed air to 75 the tool-bit held in the tool-chuck 100 as will be more fully described below.

The chuck or tool holder 100 is preferably provided with an axially disposed hole 115 therethrough, preferably hexagonal in shape 80 to fit loosely around the hexagonal or correspondingly shaped upper end of the tool-bit 116. The length of the chuck 100 is a little less than the length of the end 116 of the tool-bit so that when the tool-bit is 85 inserted in the chuck, the upper end thereof will bear squarely against the lower end of the strike-pin 112 holding the head 113 thereof firmly against the seat in the anvil 97 with the upper end of the strike-pin 112 90 projecting slightly above the inner face of the anvil 97 and in the path of the hammer-head or piston 16 when the piston-hammer is near the end of its working stroke.

The drill-bit is preferably provided with the usual collar 118 and the chuck 100 is 95 preferably provided with a yoke 119, the arms of which are pivoted at their ends on the studs 120 to the chuck 100. This yoke 119 preferably has a semicircular recess or 100 opening 121 between the arms of the yoke adapted to loosely fit around the upper end of the drill bit 117 a short distance below the collar 118 to prevent the tool-bit from slipping out of the chuck when the mechanism 105 is lifted. The semicircular recess or opening 119 is kept pressed against the upper end of the drill-bit 117 by a pair of springs 122, 122, the lower ends of which may be respectively hooked over projections or studs 123 110 on the yoke 119 and the upper ends of which may be respectively attached to pins or studs 124 rigidly mounted on the chuck 100. This construction is clearly illustrated in Figs. 1 115 and 2. The tool-bit 117 is preferably provided with a longitudinal bore 125 extending the full length thereof, with the upper end of said bore in alignment with the bore 114 through the strike-pin 112 when the parts are in the position shown in Figs. 1 120 and 2.

As above pointed out, the hub 54 consists of two sections, the upper section 53, which carries the upper cam 57 and the lower section 55 to which is secured the cam 77, these 125 sections being held together by the bolts 56 when the parts are assembled as above described. Rigidly secured to the upper section 53 of the hub 54 are outwardly extending spokes 126 which carry a rim 127. In 130

this way the hub 54, the spokes 126 and rim 127 and parts carried thereby constitute a balance or momentum wheel or rotor which is kept rotating, during the operation of the device, by the engagement of the piston-hammer with the cam 77 during a part of the downward or working stroke of the piston-hammer and in which is stored energy therein sufficient to effect the return or compression stroke of the piston-hammer 3. This rotative movement is effected by the coaction of the cross-head pin 18 with the cam 77. In Fig. 9 is shown a plane development of both cams and the different positions of the rollers 66 and 71 of the cross-head pin 18 with respect thereto throughout one complete cycle of operation.

It will be observed that the cams 57 and 77 are respectively duplex in character, that is to say, each cam is repeated at diametrically opposite sides of the circle with exactly the same outline or contour so that the rollers 66 and 71 simultaneously engage like portions of the cam, on opposite sides of the axis of the piston-hammer. The lower cam 77 is the only cam which is operative during the automatic operation of the device, the cam 57 being mainly for the purpose of starting the automatic operation as will be referred to again below.

In referring to this Fig. 9, it must be remembered that the movement of the cross-head pin 18 is a vertical reciprocation, the flat surfaces 63 and 69 of the cross-head pin 18 traveling respectively in the slots 2^a, 2 of the cylinder and by this engagement of the cross-head pin 18 with the slots 2^a and 2 in the cylinder, rotative movement of the piston-hammer about its longitudinal axis is of course prevented. At the beginning of the working stroke of the piston-hammer, the rollers 66 and 71 will be on the high points *a*, *a* of the cam 77. From these points *a* the portions *b* of the cam 77 inclines sharply downwardly to points *c*. From the points *c* the portions *d* of the cam drop substantially vertically so that from the points *d* to the end of the working stroke the rollers 66 or 71 are completely out of contact with the cam 77. During this portion of the stroke the piston-hammer is free to be impelled by the explosion at a constantly increasing speed up to the moment of impact against the strike-pin. The downward movement of the piston-hammer will be arrested by the impact of the head 16 with the strike-pin or with the anvil, or by the engagement of the cross-head pin, with the ends of the slots 2, 2^a before the lower periphery of the rollers reach the bottom surface *e* of the cam 77. When the rollers 66 and 71 of the cross-head so travel downwardly in engagement with the sharply inclined surfaces *b*, *b*, they force the cam 77 and the parts carried thereby to rotate in the direction of the arrow 128

and a great deal of energy is stored in the rotor. The momentum of the rotor keeps it rotating after the cross-head has moved out of engagement with the cam. After the piston-hammer strikes the strike-pin, the continued rotation of the rotor, by the momentum, brings the upwardly inclined portions *f* of the lower cam 77 into engagement simultaneously with the rollers 66 and 71 and the energy stored in the balance or momentum wheel will lift the rollers 66 and 71 and the piston-hammer rigid therewith vertically back to the high points *a*—*a* of the cam 77 and thus effects the compression stroke of the engine. The hub 54 with the cams 57 and 77, and spokes 126 and rim 127 carried thereby, thus form a rotor which is put into rotation by the piston-hammer during the first part, portion or fraction of the downward or working stroke thereof; that is to say, when the rollers 66 and 71 are forced against the inclined portions *b*—*b* of the cam 77 sufficient energy is stored to effect the return or compression stroke of the piston-hammer. The angle which the surface *b* makes with the vertical passing through the highest point *a* of the surface of the cam 77 is a small one as for instance, 35° and after the rollers 66 and 71 pass over the point *e* the piston-hammer moves very rapidly to the end of its downward stroke, into engagement with the strike-pin 112. The piston-hammer is out of engagement with the cam 77 during this latter part of the stroke and is free to be impelled at a constantly increasing and high rate of speed under the explosive force of the burning gases in the combustion chamber 30 during this section or latter half of its stroke. The rotative movement of the cam 77 during the working stroke of the piston-hammer may be indicated by the distance *h* in Fig. 9 which may be and is relatively small as compared with the distance *i* through which the cam rotates during the return or compression stroke of the piston. Thus it is that a relatively long slow rise may be given to the portion *f* of the cam 77 in order to impose as little work as possible upon the rotor in effecting the return stroke of the piston-hammer and the compression of the explosive charge in the explosion chamber. The contour or shape of the portion *f* of the cam 77 may, however, be considerably varied without departing from the spirit and scope of my invention as will be referred to again below.

In order to start an internal combustion engine, the piston must be reciprocated within the cylinder to draw an explosive mixture into a mixing chamber; to transfer it to the explosion chamber and to there compress it prior to the ignition thereof and in the present device, the cam 57 is for that purpose. The portion *j* of the cam 57 is preferably vertically spaced above the high

point *a* of the cam 77 by a distance substantially equal to the diameter of the rollers 66 or 71. A slight clearance is allowed at this point (as clearly indicated in Fig. 9).

6 From the point *j* the cam surface *k* inclines downwardly diverging slightly from the portion *b* of the surface of the cam 77 and extending to the point *l*. From this point a portion *m* of the cam may rise in any pre-
10 determined manner and then extend to the point *j* on the other side of the cam. The surface *k* of the cam 57 is the only surface thereof which is really operative and then only in starting the automatic operation of
15 the device. Assuming the piston-hammer 3 to be in its lowest position, the manual rotation of the rotor of the device will bring the surface *f* of the cam 77 against the rollers 66 and 71 and will lift the piston-hammer moving it upwardly toward the cylinder head 5 and drawing an explosive mixture into the mixing chamber 29. The continued manual rotation of the rotor will then bring the surface *k* of the cam 57 into engagement with the rollers 66 and 71 and this engagement will then move the piston-hammer downwardly to compress the explosive charge in the mixing chamber 29. When the rollers reach the point *l* of the cam 57,
20 the port 41 will be open and the explosive charge will be transferred from the mixing chamber 29 to the explosion chamber 30. The continued rotation of the rotor will now bring the inclined surfaces *f* of the cam 77 again into engagement with the rollers 66 and 71 to compress the explosive charge in the explosion chamber 30 and to draw a new charge into the mixing chamber 29. As the rollers 66 and 71 now roll over
25 the high points *a* of the cam 77, the explosive charge in the chamber 30 will be ignited and the automatic operation of the device will continue so long as fuel is supplied thereto. Thus it will be seen that the only
30 operative portion of the cam 57 is the portion *k* which effects the initial compression of the explosive charge chamber and to effect the transference of it to the explosion chamber. Theoretically, during the automatic operation of the device, the rollers 66 and 71 would not engage the upper cam 57.

In the embodiment of my invention shown in Figs. 1, 2 and 3 I provide, in addition to the chambers 29 and 30, a third chamber,
35 129, which is located between the piston-head 16 and the anvil 97. The hammer-head 16 reciprocating in said chamber 129 performs the double purpose of imparting a blow to the drill-bit and for compressing air which in turn may be employed to perform several functions, namely, to remove detritus or dust from the bottom or hole; for regulating and controlling the force of the blow with which the piston-hammer strikes the strike-pin
40 112, for cooling the explosion end of the

cylinder, and for clearing or cleaning the air filters, referred to again below. At the bottom of the chamber 129 is an air inlet port 130 controlled by a check valve 131, co-
45 acting with its seat 132, allowing air to be drawn through the pipe or passage 133 into the chamber 129 upon the upward movement of the hammer-head 16 but preventing any passage of air from said chamber 129 into said pipe or passage 133. The upper end of
50 the pipe 133 communicates with a chamber 134 formed in the wall of the oil pan 87 and the upper end of said pipe or passage 133 extends laterally through the wall of said pan 87 and is provided with an air filter 86 or strainer 135.

For the purpose of driving air down through the bore of the drill to remove the dust and small particles from the bottom of the hole being drilled, the upward move-
55 ment of the hammer-head 16 draws air from the outside atmosphere in through the filter 135, chamber or passage 134, pipe 133, past the check-valve 131 into the chamber 129 and the downward movement of the hammer-head forces the air so drawn into the chamber 129 down through the bore 114 in the strike-pin and through the bore 125, through the tool-bit 117 to the bottom of the hole.

For the purpose of regulating the force of
60 the blow imparted to the strike-pin 112 and through it to the tool-bit 117, I provide a port 136 also communicating with the bottom of the chamber 129 through the wall of the cylinder 1. This port 136 by a pipe or
65 passage 137 communicates with a chamber 138 in a pressure controlling valve 139. This valve may comprise a movable valve member 140 adapted to be normally held seated against the valve seat 141 by a spring 142 compressed between a piston-head 143 and a cap 144 closing the lower end of the cylinder 145. The valve member 140 is provided with a stem 146 extending longitudinally through the cap 144 and the outer end of
70 said stem 146 is preferably provided with an adjusting member 147 having radial arms or wings 148 adapted to ride or slide over a pair of arc-shaped cams 149 slowly rising from the underside of the cap 144 and which may be provided with suitable notches 150 for the purpose of retaining the wings or arms in any adjusted position with respect thereto. By turning the member 147, the pressure with which the valve member 140
75 presses against the valve seat 141 may be delicately adjusted.

The diameter of the piston-head 143 is considerably larger than the diameter of the valve seat 141. The ratio of the area of the piston-head 143 to the area of the valve seat 141 and the pressure of the springs 142 may be so proportioned that until the pressure of the compressed air under the hammer-head 16 and in the chamber 129 reaches a prede-
80

terminated point, the valve member 140 will remain seated on the valve seat 141 and up to that pressure substantially all the air being compressed in the chamber 129 may be forced down through the bore 114 of the strike-pin or up to any other point to which air from the compression chamber 129 may be desired, but when the pressure in said chamber rises above that predetermined point, then the piston 143 will be forced downwardly to lift the valve member 140 off its seat, and to permit the air to escape into the passage 151 and thence through a passage 152 formed in the wall of the lubricating oil pan 87 back into the inlet chamber or passage 134.

This discharge of air from the pressure controlling valve 139 back into the chamber 134 is for a very useful purpose. It will be appreciated that in rapidly drilling rock and blowing the detritus from the hole being drilled as fast as the same is formed will, in many instances, cause the air surrounding the mechanism to be filled with fine dust. To take air commingled with this dust back into the chamber 129 of the drill would be likely to injure the mechanism. It would tend to cause the parts to wear very rapidly. The air filter 135 is to prevent this dust from being drawn in the chamber 129, but under these circumstances the accumulation of the dust in the filter 135 would be considerable and under ordinary circumstances would necessitate a frequent replacement of the filter cloths or wires used in the filter to arrest the dust. When, therefore, the controlling valve is so adjusted as to lift the valve 140 off its seat at or near the end of the downward stroke of the hammer-head, air at the high pressure then existing in the chamber 129 will be driven through the conduit or passage 151 into the chamber 134 and out through the filter 135. This sudden puff of air under high pressure occurring at the end of the compression stroke will blow the dust accumulating on the outer sides of the filter cloths or wires 135 outwardly and off of the same thus keeping them clear of any considerable accumulation of dust for a long time. It is believed that from the above, the operation of this portion of the apparatus will be clear. The upward stroke of the hammer-piston 16 draws air through the filter and the dust collects on the outside of the filter cloths or wires. At the end of the compression stroke air at high pressure is forced in the reverse direction through these filter cloths and clears the filter cloths of the filter 135 of the dirt accumulating thereon. In some instances the valve may be adjusted so that it is just off its seat so that some air will pass therethrough throughout the working stroke.

It may be desirable to use some of the air compressed in the chamber 129 to cool

the cylinder head 5. For this purpose I may provide the chamber 129 with another port 153 (see Fig. 5) to which is attached a pipe 154 which may be passed through suitable openings extending longitudinally through the threaded projections 1^a and 1^b on the surface of the cylinder 1. The upper end of the pipe 154 may be provided with a valve 155 adapted to open and close the passage through said pipe 154. When said valve 155 is opened air from the chamber 129 may pass upwardly through the valve 155 through the pipe 156, the upper end 157 of which is down turned to discharge the air against the top side of the cylinder head 5. Any suitable coupling 158 may be provided between the pipes 154 and 156 to provide for the convenient removal of the pipe 156 when its presence is not necessary or desirable.

By the above provisions the force with which the hammer-head 16 impinges against the strike-pin 112 may be nicely adjusted, that is to say the pressure produced in the chamber 129 near the end of the stroke may be made sufficient to diminish, when so desired, the force of the blow with which the strike-pin is struck by the hammer 16. This operation may be of considerable assistance in starting the device when the end of the tool may not be in engagement with the rock to be drilled or in seating the drill to begin the drilling operation when the full force of the blow might not be needed or desirable.

The tank or fuel reservoir 36 is preferably supported between and on a pair of stiff tubular supports 159, the upper ends of which are bolted or otherwise rigidly secured to lugs 160—160 rigid with the cylinder-head and which may extend rearwardly and downwardly from the sleeves 10 on the cylinder-head 5. The lower ends of the supports 159 may be provided with slots 159^a which fit over the opposite ends respectively of a stud 161 rigidly secured to the lug 161 extending radially from the ring 103. As clearly shown in Fig. 2, this tank 36 may be hung on said tubular supports 159 by straps or brackets 162—162 secured to the opposite sides of the tank 36. The top of the tank 36 may be provided with a suitable pocket or recess 163 adapted to contain an induction coil 164 and a condenser 165 of the ignition system (see Figs. 2 and 11).

In the construction illustrated in Figs. 1 and 2 fuel is supplied from the tank 36 to the carbureter 31 by an air compressor 166 which may be mounted in the tank. When the knob 167 is drawn up by hand to elevate the piston 168, the check valve 169 remains closed and air passes through the flexible packing 170 surrounding the piston 168. When the knob is depressed, air enters the cylinder above the piston 168 through the

- port 172 and the air trapped in the lower end of the cylinder is forced through the check valve 169 into the tank 36 where it creates a pressure above the level of the liquid fuel therein, to force the fuel through the tube 37 to the carbureter, the pressure in the tank 36 being registered on a pressure gage 173. In the rear of the tank 36, the two tubular supports 159 may be rigidly connected together by a cross-bar 174 upon which may be pivoted, in any suitable manner, a sheet metal guard or plate 175, the lower end 176 of which may be transversely curved to fit against the thigh or leg of one operating the drill. In this way a substantial part of the weight of the drill may be supported on the leg of the operator when a hole is being drilled at an angle to the perpendicular. This pivoted plate 175 will turn on the rod 174 and adjust itself to the leg of the operative and assist him in steadily supporting the device in any desired inclined position, and in carrying the device from one place to another.
- 25 Referring now more particularly to Figs. 2 and 11, on the bottom of the tank 36 is preferably secured a block 177 of insulating material carrying two binding posts 178 and 179 to which the opposite ends of a battery 180 may be attached by leads 181, 182 respectively. The binding post 179 is preferably grounded to the machine by a wire 193. The other binding post may be connected by a wire 184 with binding post 185 which in 30 turn may be connected to one terminal of the primary winding 186 of the induction coil 164. The other end of the primary winding 186 may connect with a binding post 187 to which may be connected a wire 188 leading 35 to the binding post 189 of an insulated block 190 of the contact device 191. This contact device may be of any suitable construction but the one I prefer to use comprises a longitudinally adjustably fixed contact point 192 and a movable contact point 193 cooperating therewith and intermittently engaging said fixed contact point when the projections 194 of the plates 195, mounted at diametrically opposite points on and carried by the spokes 50 40 of the rotor travel under and engage and lift the movable contact 193. The movable contact point 193 is normally kept in its lowermost position and out of contact with the fixed contact by a coiled spring 196 as 45 clearly shown in Fig. 11. These contact points are preferably carried or mounted in a housing or casing 197 preferably rigidly secured to a longitudinal slidable rod 198 mounted in bearings 199 at opposite ends of a radial 50 slot or cut away portion 200 in the rim of the hood or cover 49. By a slight adjustment of the contact device 191 forwardly or backwardly, the spark in the explosion cylinder may be advanced or retarded.
- 55 One side of the condenser 165 which, as

above stated, is preferably mounted in the recess 163 of the tank or reservoir 36, may be connected to binding post 201 and thence by wire 202 to the wire 188. The other side of the condenser 165 is preferably grounded 70 to the machine, by any suitable connection, 203. In this way the make and break contact points 192 and 193 are bridged by the condenser 165.

The secondary circuit of the ignition system 75 comprises the secondary winding 204, one end of which may be connected to binding post 205 and thence by wire 206 to the spark plug 14 which is grounded to the machine in any suitable manner. The other end of the 80 secondary winding 204 may be grounded to the machine by a suitable connection 207.

Any suitable means for supplying a suitable amount of lubricant to the cams, cross-head, and lower piston or hammer piston 85 may be employed but in Figs. 1, 2 and 8 I have illustrated one construction wherein the lower section 53 of the hub 54 may be provided with inclined tubes 208 extending therethrough with the lower ends 209 thereof projecting forwardly in the direction of the rotation of the rotor. As the rotor revolves relatively rapidly, oil will be forced upwardly through the inclined tubes 208 and will be discharged in a stream directed 95 against the engaging surfaces of the cams 57 and 77, and against all of the interior of the upper section 53 of the hub 54. The pan 87 will normally contain a suitable amount of oil and the packing rings 85 and 90 are 100 for retaining the oil in the pan. In this way the piston rod 19, the cross-head pin, the cams and the roller bearings of the rotor are kept thoroughly lubricated. An oil duct 210 may also be provided to permit the oil 105 thrown over the upper edge of the cam 57, over the balls 52 and between the ball races 50 and 51, and outwardly over the ball race 51, to fall back into the pan or tank 87.

There will be no special need of any packing rings around the strike-pin 112 or around the anvil 97, because the oil which works past the hammer-head 16 into the chamber 129 will form an oil seal between the walls of the cylinder 1 and the anvil 115 and between the anvil and the strike-pin 112. The over-hanging inner top wall 211 of the pan 87 is for the purpose of preventing the oil from running out over the top of the pan when the tool is placed in 120 an inclined position. With this construction the drill may even be inverted without spilling oil from the pan 87.

When the machine has been once set in motion by manually rotating the rim 127 of 125 the rotor until the first explosion takes place in the explosion chamber 30, the piston-hammer will be reciprocated on the principle of a two-cycle single-acting explosion engine. On the down stroke the explosive mixture 130

will be compressed in the chamber 29. The cross-head pin will first traverse the portions *b*—*b* of the lower cam 77 and then it will complete the downward stroke entirely 5 out of contact with the cam 77. At the end of its stroke, the hammer-head of the piston-hammer will engage the projecting end of the strike-pin 112 and impart a blow to the tool-bit 117. On its down stroke the air 10 contained in the chamber 129 will be compressed and driven down the port or hole 114 in the strike-pin and thence through the bore 125 on the tool-bit to the bottom of the hole being drilled and will forcibly eject 15 the small chips or detritus from the hole leaving the bottom of it clear for the engagement therewith of the tool-bit. If at or near the end of the downward or working stroke the pressure of the air in the chamber 20 129 be greater than a predetermined pressure to which the valve 139 has been set, this pressure controlling valve 139 will allow the excess air to pass out through the valve seat 141 and the passages 151 and 160 to the 25 chamber 134 whence it will pass outwardly through the filter 135 removing the dust which may have collected on the outside of the filter plates or screens 135^a therin.

After the cross-head pin 18 has left the 30 surfaces *b*—*b* of cam 77 the rotor continues to rotate by momentum and brings the opposite inclined portions *f*—*f* of the cam 77 into simultaneous engagement with the rollers 66 and 71 respectively on the cross-head 35 pin and will lift the piston-hammer to effect the return or compression stroke of the piston-hammer. This upward movement of the piston-hammer will draw air into the chamber 129 through the filter 135, chamber 134, 40 conduit 133 and past the check valve 132, it being understood that as soon as the pressure in the chamber 129 drops to a point lower than the predetermined pressure for which the valve 139 is set, the valve 142 immediately closes on its seat 141 and air can 45 no longer pass through the pressure control valve 139.

In Fig. 15 is illustrated a modified construction for conducting the compressed air 50 from the chamber 129 and conducting it to the tool-bit 117. Instead of providing the strike-pin with an axially arranged bore extending therethrough, as in the previously described embodiment of my invention, the 55 strike-pin 112' is substantially solid except that it may be provided with a short hole 212 at the lower end thereof which communicates through a radial passage 213 with an annular recess 214 in the outside thereof 60 forming a small chamber, when the strike-pin is positioned in the anvil 97'. The anvil 97' is provided with a radial passage 215 which communicates with the chamber 214 at its inner end and registers at its outer end 65 with a similar passage 216 through the wall

of the cylinder. The outer end of the passage 216 communicates through a pipe 217 with a check valve 218, of any approved type, and the other side of the check valve is connected by a pipe 219 with a passage 70 220 passing through the walls of the cylinder into the compression chamber 129 just above the inner end of the anvil 97'. In this way the air compressed under the hammer-head 16 in the compression chamber 129 75 passes out through the port 220 and by and through the check-valve 218 to the channel 214 and thence to the bore of tool-bit 117. The width of the channel 214 is such that when the strike-pin advances in the anvil 80 under the blow imparted thereto by the piston-hammer the hole or port 215 through the anvil 97' will not be closed or cut off, and air will be free to continuously flow into the bore or tool-bit throughout the working 85 stroke of the piston-hammer.

In Fig. 16 is illustrated a slightly modified construction wherein the fuel mixing chamber is located between the hammer-head and the anvil at the lower end of the cylinder 1 90 and the air compression chamber is located between the working-piston section of the piston-hammer and the intermediate cylinder-head. The mixing chamber 29' communicates through a port 32' with the carbureter 31. Also communicating with the mixing chamber 29' is a port 39' which communicates through the transfer passage 40' with the inlet 41 leading into the combustion chamber 30 when the piston 15 is at or near the end of its downward working stroke. This transfer passage 40' consists in this instance of a pipe passing through the flanges 1^a' and 1^b' on the outside of the cylinder 1'. In this instance these flanges or rings are 105 made all a little larger than that used in the construction previously described for the purpose of providing ample space for the passage of this tube or pipe 40' therethrough. The carbureter 31 communicates 110 with the bottom of the tank 36 by a pipe 37' through which fuel may be conducted by gravity to the carbureter. The air compression chamber 129' is beneath the working piston 15. An air inlet port 181' is in communication with this chamber 129' and the passage of air therethrough is controlled by a check-valve 132'. Also in communication with the chamber 129' is an air outlet port 220' which by a pipe or passage 219' communicates with a check-valve 218' near the lower end of the cylinder. This pipe 219' also preferably passes through the enlarged flanges 1^a', 1^b' on the outside of the cylinder 125 and between the main portion or body of the cylinder and the rotor mounted around the cylinder. Below the check-valve 218' the compressed air from the chamber 129' is conducted to the tool-bit in the same manner as that described in connection with Fig. 13; 120

that is to say, through the pipe 217, passage 216 through the cylinder walls, through passage 215 through the anvil 97', and thence through the chamber 214 and the passage 5 213 with the short bore 212 in the end of the strike-pin 112'.

In Fig. 16 I have also shown another slight change in construction. The bore through the cylinder 1' in this instance is 10 not of uniform diameter throughout substantially the whole length of the cylinder, for I provide a seat or shoulder 24' therein upon which the intermediate cylinder-head 21 is seated. In this form of my invention 15 the intermediate cylinder-head 21 which in construction is like that in Fig. 7, is held firmly against said seat 24' and the parts thereof are held firmly together by the upper screws 27 in the manner heretofore described.

It will thus be seen that the two types of construction as illustrated in Figs. 1 and 2, and in Fig. 16 each have advantages. In the construction of Figs. 1 and 2, the fuel mixing chamber is immediately beneath the working piston 15 and the transfer passage from the mixing chamber 29 to the combustion chamber 30 is short. In said construction the air compression chamber is situated 25 closely adjacent the upper end of the tool-bit so that the air compressed therein may be readily discharged directly through the strike-pin to the upper end of the tool-bit. The advantages of these features of construction must be obvious.

But, on the other hand, in the construction illustrated in Fig. 16 the carbureter is located at the lower end of the cylinder so that the fuel from the tank 36 may readily flow 40 by gravity through the pipe 37' thereto, thus dispensing with the air pump for forcing all the fuel in the tank to the carbureter. This advantage of this construction is now also apparent.

45 I have found that it may be advisable to provide special means for insuring the passage of the compressed air from the strike-pin to the interior bore 125 of the tool 117. This may be accomplished by enlarging the 50 upper end of the hole 115 through the tool-holder or chuck 100 and seating therein a packing washer 221 having a central flange or projection 222 which fits against the outside of the shank 116 of the tool 117 and 55 surrounding this flange is a tight ring 223 which compresses the flat portion of the packing between the lower end of the anvil and the bottom of the recess in the tool-holder 100 and also presses the flange 222 60 tightly against the shank of the tool. If the shank of the tool be hexagonal in shape in cross-section, then the flange 222 of the packing washer should be hexagonal to snugly bear against the flat sides of the shank and 65 the ring 223 may also have a corresponding

hexagonal hole therethrough. If the shank of the tool be circular or any other shape in cross-section, the packing may be made to fit and correspond thereto. This construction prevents the air discharged from the 70 strike-pin from leaking out through the tool-holder or chuck 100 around the upper end 116 of the tool and insures the conveying of the compressed air down into and through the bore 125 of the tool to the bottom of the 75 hole being drilled.

I also find it advisable to so construct, arrange and proportion the parts that the rollers 66 and 71 will be prevented from actual contact with the cam 77 at the end of the 80 downward or working stroke. The rollers 66 and 71 are located at quite a distance from the exterior surface of the intermediate portion 17 of the piston-hammer and if these rollers were allowed to strike the 85 cams a hard blow the cross-head pin 18 might become bent or sprung or loosened and the rollers and cam might be flattened or even broken, all of which would be detrimental to the successful operation and construction of 90 the machine. I therefore prefer to so position the slots 2 and 2^a through the cylinder 1 that the lower ends thereof may be engaged by the cross-head pin close to the exterior surface of the intermediate portion 17 95 when the force of the impact of the piston-hammer on the strike-pin and anvil is so great that it cannot be or is not absorbed by the springs 109. The lower cylindrical surface of the portion 59 of the cross-head pin 100 18, immediately under the flattened portion 69 thereof, is therefore arranged to engage at the end of an abnormally long working stroke with the bottom of the slot 2 and the flat underside of the cross-head pin 18 immediately under the flattened side surfaces 63 thereof is also arranged to simultaneously engage with the flat lower surface of the slot 2^a. The reason for the above construction must be plain. Every stroke of the piston-hammer should cause the tool to penetrate into the material being drilled or bored. But in drilling, a soft spot or cavity might be encountered by the cutting edges of the tool or the entire drill might be lifted while 110 running and the blow on the strike-pin might force the tool far below the upper surface of the anvil. In such an event, a substantial part of the impact on the piston-hammer would be received by the anvil 115 97 but if this blow were a heavy blow, the springs 109 might not absorb all of the energy of the blow so imparted to the anvil and the rollers might strike on the bottom part e of the cams 77 were it not for the fact 120 that I so position the cross-head pin and the slots 2 and 2^a that the cross-head pin will strike the lower ends of the slots 2 and 2^a before the rollers 66 and 71 can ever reach the 125 bottom of the cam 77. In other words, when 130

the cross-head pin is in engagement with the lower surfaces of the slots 2 and 2^a there will always be a slight clearance between the rollers 66 and 71 and the surface *e* of the cam 77.

5 In the embodiment of my invention illustrated in Figs. 15 and 16 the anvil 97' is prevented from rotating within the cylinder in order to maintain the passage 215 in registration with the passage 216. For this purpose I may provide the enlarged lower head of the anvil with a rigid pin 224 projecting radially a short distance beyond the periphery of the head into a short vertical slot 225 in the end of the cylinder. The anvil is thus free to move slightly longitudinally, when struck by the piston-hammer, but is restrained from rotative movement.

From the foregoing it will be plain that 20 I have provided a structure wherein the cylinder is divided by the piston-hammer into three compartments, namely, the combustion or explosion chamber 30, the fuel intake and mixing chamber 29 and the air compression chamber 129, all of substantially the same length, and of nearly the same capacity and providing small clearances for the parts of the piston-hammer co-acting therewith. As a result of this, substantially all of 30 the fuel drawn in the chamber 29 on the non-working stroke is transferred at a relatively high pressure to the explosion chamber 30 at or near the end of the working stroke of the piston-hammer, the explosion chamber is completely cleared of the products of combustion of the previous working stroke and filled with a clean explosive mixture, and substantially all of the air is expelled at a relatively high pressure 40 from the air compression chamber 30 on each working stroke of the piston-hammer.

In the form of my invention shown in Figs. 1 and 2, the actual capacity or full volume of the transfer chamber 29 and passage 45 40 may be even less than that of the explosion chamber 30, because of the presence of the piston rod 3 in the chamber 29, but the capacity or full volume of the air compression chamber 29 is substantially the same as 50 that of the explosion chamber 30.

In the form of my invention shown in Fig. 16, however, the converse may apply for the capacity of the transfer chamber 29' and the passage 40' is substantially equal to 55 that of the explosion chamber 30, although the diameter of the chamber 29 may be slightly less than that of the explosion chamber 30, and the capacity of the air compression chamber 129' may be smaller than the 60 capacity of the explosion chamber 30, because of the presence of the piston rod therein. These differences are slight, however, and may be substantially equalized or varied by the clearances and volumes of the 65 passages leading to and from these cham-

bers, and the diameters of the bore in the cylinder.

This construction makes possible the transfer of fuel from the fuel intake and transfer chamber to the explosion chamber 70 at a much higher pressure and velocity than can be attained in any of the ordinary two-cycle explosion engines, and to transfer to the explosion chamber on each working stroke of the piston, substantially all of the 75 charge contained in the fuel intake and transfer chamber, an operation impossible of attainment in any other form or type of two-cycle explosion engine of which I am aware. It also makes it possible to so compress air therein that the compressed air may be conveyed to the bottom of the hole being drilled as a series of puffs or pulsations, at 80 relatively high pressure and velocity, to effectively remove detritus from the bottom 85 of the hole being drilled, for keeping the bottom of the hole clean for the cutting action of the drill.

While I have described with some particularity the details of several forms of my 90 invention, I do not wish my invention to be construed as limited to the exact constructions shown, since many changes may be made therein without departing from the spirit and scope of my invention as set forth 95 in the appended claims.

Having thus described my invention what I claim and desire to protect by Letters Patent of the United States is:

1. In an impact tool the combination of 100 a cylinder, a piston-hammer reciprocable therein on the principle of an internal combustion engine, said piston-hammer forming with the cylinder a chamber in said cylinder into which air is drawn by said 105 piston-hammer during the return or compression stroke of said piston-hammer and in which chamber said air is compressed by said piston-hammer during the power stroke of said piston-hammer and means to 110 conduct some of the air, so compressed, from said cylinder, on every power stroke of said piston-hammer, to the bottom of the hole being drilled to remove detritus therefrom.

2. In an impact tool, the combination of 115 a cylinder, a piston-hammer reciprocable therein on the principle of an internal combustion engine, said piston hammer forming with the cylinder a chamber in said cylinder into which air is drawn by said piston-hammer during the return stroke of said piston-hammer and in which chamber air is compressed in said cylinder by said piston-hammer during the power stroke of said piston-hammer, and means to conduct some of the 120 air so compressed from said chamber to the combustion end of said cylinder to cool said 125 end of said cylinder.

3. In an impact tool, the combination of 130 a cylinder, a piston-hammer reciprocable

- therein on the principle of an internal combustion engine, said piston-hammer forming with said cylinder a chamber in said cylinder into which air is drawn by said piston-hammer during the return stroke of said piston-hammer and in which chamber air is compressed by said piston-hammer during the working stroke of said piston-hammer, means to conduct some of the air so compressed to the bottom of the hole being drilled to remove detritus therefrom, and means to conduct some of the air from said chamber to the combustion end of said cylinder to cool said end of said cylinder.
4. In an impact tool, the combination of a cylinder, a piston-hammer reciprocable therein on the principle of an internal combustion engine, an air filter, said piston-hammer cooperating with said cylinder to draw air inwardly through said filter into a portion of said cylinder during the return stroke of said piston-hammer and to compress said air in said cylinder during the power stroke of said piston-hammer, and means to conduct some of the air, so compressed, at high pressure, on every power stroke of said piston-hammer outwardly through said filter to clean the same of any accumulation of dust thereon.
5. In an impact tool, the combination of a cylinder, a piston-hammer reciprocable therein on the principle of an internal combustion engine, an air filter, said piston-hammer cooperating with said cylinder to draw air through said filter into a portion of said cylinder during the return stroke of said piston-hammer and to compress said air in said cylinder during the power stroke of said piston-hammer, a valve operative to limit the pressure to which air may be compressed in said portion of said cylinder and means to convey the air passing said valve backwardly through said filter to clean the same on every power stroke of said piston-hammer.
6. In an impact tool, the combination of a cylinder, a piston-hammer reciprocable therein on the principle of an internal combustion engine, said piston-hammer dividing the interior of said cylinder into an explosion chamber, a fuel intake chamber, and an air compression chamber, said piston-hammer cooperating with said cylinder to draw air into said air compression chamber on the compression stroke of said piston-hammer and to compress said air in said air chamber on the power stroke of said piston-hammer and a valve adjustable to vary, limit and regulate the pressure to which air may be compressed in said air compression chamber of said cylinder to regulate the force of the blow delivered by said piston-hammer.
7. In an impact tool, the combination of a cylinder, a piston-hammer reciprocable therein on the principle of an internal combustion engine, said piston-hammer cooper-
- ating with said cylinder to draw air into said cylinder on its compression stroke and to compress air in said cylinder on its forward or working stroke, means to receive the impact of said piston-hammer at the end of said working stroke and to transmit said impact to the shank of a tool, and means to limit and to vary the limit to which air may be compressed by said piston-hammer to regulate the force of the impact of said hammer.
8. In an impact tool, the combination of a cylinder, a piston-hammer reciprocable therein on the principle of an internal combustion engine, said cylinder being also provided with an air compression chamber, said piston-hammer cooperating with said cylinder to draw air into said air compression chamber on its compression stroke and to compress air in said chamber on its forward or working stroke, means to receive the impact of said piston-hammer at the end of the working stroke, and means to regulate and to vary the limit to which said air may be compressed by said piston-hammer to regulate and vary the force of the impact of said piston-hammer on said impact receiving means.
9. In an impact tool, the combination of a cylinder, a piston-hammer reciprocable therein on the principle of an internal combustion engine, means to supply fuel to said tool, means to receive the impact of said piston-hammer at the end of the working stroke and to transmit said impact to a tool, and means independent of said fuel supply means to regulate and vary the force of the said impact on said tool.
10. In an impact tool, the combination of a cylinder, a piston-hammer reciprocable therein on the principle of an internal combustion engine, said piston-hammer cooperating with the cylinder to draw air into a portion of said cylinder on its compression stroke and to compress said air in said cylinder on its forward or working stroke, a conduit for conducting incoming air to said portion of said cylinder, a screen or filter in said conduit to remove dust from said incoming air, and means operative on said working stroke to convey air so compressed by said piston-hammer and at a predetermined high pressure from said cylinder to said filter, whereby the air passing outwardly through said screen or filter removes any accumulation of dust from the outer side of said screen or filter.
11. In an impact tool, the combination of a cylinder, a one-piece piston-hammer reciprocable therein on the principle of a single-acting two-cycle combustion engine and having a cylindrical hole extending transversely therethrough and a rectangular recess at one end of said hole of a width not less than the diameter of said hole, and a cross-head

- pin having an intermediate cylindrical portion adapted to tightly fit into said cylindrical hole in said piston-hammer, a rectangular portion adapted to fit into said recess, a pair of vertical parallel bearing surfaces adjacent said rectangular portion and spaced apart a distance not less than the width of said rectangular portion, and a pair of vertical parallel surfaces adjacent the other end of said cylindrical portion, spaced apart a distance less than the diameter of said cylindrical portion, said cylinder being provided with a pair of diametrically disposed longitudinally extending slots therethrough, one slot being substantially wider than the other slot, whereby said cross-head pin is insertable through the wider of said slots into said cylinder, into and through said piston-hammer, and the last-mentioned vertical parallel surfaces into engagement with the sides of the narrower of said slots in said cylinder and the first-mentioned parallel surface into engagement with the sides of the wider of said slots.
12. In an impact tool, the combination of a cylinder, a one-piece piston-hammer reciprocable therein on the principle of a single-acting two-cycle combustion engine and having a cylindrical hole extending transversely therethrough and a rectangular recess at one end of said hole of a width not less than the diameter of said hole, a cross-head pin having an intermediate cylindrical portion adapted to tightly fit into said cylindrical hole in said piston-hammer, a rectangular portion adapted to fit into said recess, a pair of vertical parallel bearing surfaces adjacent said rectangular portion and spaced apart a distance not less than the width of said rectangular portion, and a pair of vertical parallel surfaces adjacent the other end of said cylindrical portion, spaced apart a distance less than the diameter of said cylindrical portion, said cylinder being provided with a pair of diametrically disposed longitudinally extending slots therethrough, one slot being substantially wider than the other slot, whereby said cross-head pin is insertable through the wider of said slots into said cylinder, into and through said piston-hammer, and the last-mentioned vertical parallel surfaces into engagement with the sides of the narrower of said slots in said cylinder and the first-mentioned parallel surface into engagement with the sides of the wider of said slots, and means to lock said cross-head pin in said hole to prevent longitudinal movement of said cross-head pin in said hole in said piston-hammer.
14. In an impact tool, the combination of a cylinder, a piston reciprocable therein on the principle of an internal combustion engine, a rotor surrounding said cylinder coaxially therewith and rotated by said piston-hammer, and an oil pan rigidly secured to said cylinder, surrounding said cylinder, extending upwardly to surround the lower portion of said rotor and having a flange at the top thereof extending inwardly close to the outer surface of said rotor to prevent the escape of oil over the top of said pan when said cylinder is inclined in any direction.
15. In an impact tool, the combination of a cylinder, a piston reciprocable therein on the principle of an internal combustion engine, a rotor surrounding said cylinder coaxially therewith and rotated by said piston-hammer, and an oil pan rigidly secured to said cylinder, surrounding said cylinder, extending upwardly to surround the lower portion of said rotor and having a flange at the top thereof extending first inwardly and then downwardly close to the outer surface of said rotor to prevent the escape of oil over the top of said pan when said cylinder is inclined in any direction.
16. In an impact tool, the combination of a cylinder, a piston-hammer reciprocable therein on the principle of an internal combustion engine, said piston-hammer cooperating with the cylinder to draw air into a portion of said cylinder on its compression

- stroke and to compress air in such portion of said cylinder on its forward or working stroke, a rotor surrounding said cylinder and rotated by said piston-hammer, a pan 5 mounted on and surrounding said cylinder and extending upwardly and over and around the lower part of said rotor and provided with an air inlet conduit, an air filter at the outer end of and communicating with said 10 conduit, a connection between said filter and said air compressing portion of said cylinder, a check valve in said connection between said filter and said cylinder, a pressure control valve for permitting air to escape from 15 said cylinder when the pressure thereof attains a predetermined point, and means to convey the air so escaping from the cylinder through said valve, through said pan, and into said air inlet conduit and through said 20 filter to the atmosphere.
17. In an impact tool, the combination of a cylinder, a piston-hammer reciprocable therein on the principle of an internal combustion engine, said piston-hammer dividing said cylinder into an explosion chamber, a fuel intake chamber, and an air compression chamber, and cooperating with the cylinder to draw air into said air compression chamber on its compression stroke and to 25 compress air in said air compression chamber on its forward or working stroke, an anvil 30 yieldingly mounted in said cylinder, and a strike-pin slidingly mounted in said anvil to receive the impact of said piston-hammer 35 at the end of the working-stroke thereof and having a hole or bore at the center of the lower end thereof, the air so compressed being forced by said piston-hammer from said air compression chamber into said hole or 40 bore in said strike-pin.
18. In an impact tool, the combination of a cylinder, a piston-hammer reciprocable therein on the principle of a single-acting explosive engine, said piston-hammer dividing said cylinder into an explosion chamber, a fuel intake chamber and an air compression chamber, and cooperating with the cylinder to draw air into said air compression chamber on its compression stroke and 45 to compress air in said air compression chamber on its forward or working stroke, an anvil mounted in the end of said cylinder, a tool-chuck adapted to receive the shank of a tool, means to yieldingly hold 50 said chuck against said anvil and against the end of said cylinder, and a strike-pin 55 slidingly mounted in said anvil to receive the impact of said piston-hammer and having a hole or port therein and adapted to normally 60 engage said tool, the air so compressed by said piston-hammer being forced by said piston-hammer from said chamber through said hole or port in said strike-pin to the shank of a hollow drill.
- 65 19. In an impact tool, the combination of a cylinder, a piston-hammer reciprocable therein on the principle of a single-acting explosive engine, said piston-hammer dividing said cylinder into an explosion chamber, a fuel intake chamber, and an air compression chamber, and cooperating with the cylinder to draw air into said air compression chamber on its compression stroke and to compress air in said air compression chamber on its forward or working stroke, an anvil mounted in the end of said cylinder, a tool-chuck adapted to receive the shank of a hollow tool, means to yieldingly hold said chuck against said anvil and against the end of said cylinder, a strike-pin 70 slidingly mounted in said anvil to receive the impact of said piston-hammer and having a hole or port in communication with said compression chamber and a packing mounted in said chuck and adapted to engage the outer surface of said shank to prevent the passage of air from said strike-pin out and over the outer surface of said shank.
20. In an impact tool, the combination of a cylinder, a piston-hammer comprising a working-piston, a hammer-piston and a rigid connection between said pistons, a cylinder head closing the outer end of said cylinder adjacent said working-piston and forming in said cylinder an explosion chamber, a head closing the opposite end of said cylinder adjacent said hammer-piston and forming therebetween a chamber in said cylinder, an impact receiving member fitted to slide through said last-mentioned head and receive the impact of said piston-hammer at the end of the working stroke thereof, an intermediate cylinder head forming in said cylinder a chamber between said intermediate cylinder head and said working-piston, one of said two last-mentioned chambers being provided with a fuel intake port and with a fuel discharge port communicating with said combustion chamber at the end of the working stroke of said piston-hammer, whereby fuel is drawn into said chamber through said inlet port on the non-working stroke of said piston-hammer, is compressed therein by said piston-hammer on the working stroke, and is forced through said exit port into said combustion chamber by said piston-hammer at the end of said working stroke, the other of said two last-mentioned chambers being provided with an air inlet port, and means to conduct the air compressed therein by said piston-hammer during the working stroke to and through said impact receiving member to remove detritus from the bottom of the hole being drilled.
21. In an impact tool, the combination of a cylinder, a piston-hammer comprising a working-piston, a hammer-piston and a rigid connection between said pistons, a cylinder head closing the outer end of said cylinder adjacent said working piston and

- forming in said cylinder a combustion chamber, a head closing the piston end of said cylinder adjacent said hammer-piston and forming therebetween a compartment in said cylinder, an impact receiving member fitted to slide through said last-mentioned head and to receive the impact of said piston-hammer at the end of the working stroke, an intermediate cylinder head forming in said cylinder a compartment between said intermediate head and said working piston, one of said compartments being provided with a fuel intake port and with a fuel discharge port communicating with said combustion chamber at the end of the working stroke of said piston-hammer whereby fuel is drawn into said compartment through said inlet on the non-working stroke of said piston-hammer, is compressed therein by said piston-hammer on the working stroke thereof and is forced through said discharge port into said combustion chamber by said piston-hammer at the end of said working stroke, the other of said two compartments being provided with an air inlet port and with an air discharge port whereby air is drawn into said compartment on the non-working stroke of said piston-hammer and is expelled therefrom through said discharge port by said piston-hammer on the working stroke, and means to convey said compressed air to a hollow drill and therethrough to the bottom of the hole being drilled.
22. In an impact tool, the combination with a cylinder, a piston-hammer slidable therein and comprising a working piston, a hammer-piston and a rigid connection between said pistons, of a cylinder head closing that end of the cylinder adjacent said working piston and forming a combustion chamber therebetween, a head closing the opposite end of said cylinder forming a compartment in said cylinder between said head and said piston-hammer, an impact member slidable in said last-mentioned head and adapted to receive the impact of said piston-hammer at the end of the working stroke, an intermediate cylinder head closing said cylinder between said pistons and forming a compartment in said cylinder between said head and said working piston, one of said compartments being a fuel intake and transfer chamber and the other an air compression chamber, and means to conduct air from said air compression chamber to the bottom of the hole being drilled to remove detritus therefrom.
23. In an impact tool, the combination of a cylinder, a piston-hammer comprising a working piston, a hammer-piston and a rigid connection between said pistons, a cylinder head closing the outer end of said cylinder adjacent said working piston and forming a combustion chamber in said cylinder, a head closing the opposite end of said cylinder adjacent said hammer-piston and forming a compartment in said cylinder between said head and said hammer-piston, an impact receiving member in said last-mentioned head and adapted to receive the impact of said piston-hammer at the end of the working stroke thereof, and an intermediate cylinder head closing said cylinder between said pistons and forming a compartment in said cylinder between said head and said working piston, one of said compartments being a fuel intake and transfer chamber and the other an air compression chamber, the lengths of said three chambers being substantially equal whereby substantially all of the charge in said fuel intake and transfer chamber is transferred to said explosion chamber on each working stroke of said piston-hammer and substantially all of the air compressed in said air compression chamber is expelled therefrom at the completion of the working stroke of said piston-hammer.
24. In an impact tool, the combination of a cylinder, a piston-hammer comprising a working piston, a hammer-piston and a rigid connection between said pistons, a cylinder head closing the outer end of said cylinder adjacent said working piston and forming a combustion chamber in said cylinder, a head closing the opposite end of said cylinder adjacent said hammer-piston and forming a compartment in said cylinder between said head and said working piston, one of said compartments being a fuel intake and transfer chamber and the other an air compression chamber, the lengths of said three chambers being substantially equal whereby substantially all of the charge in said fuel intake and transfer chamber is transferred to said explosion chamber on each working stroke of said piston-hammer and substantially all of the air compressed in said air compression chamber is expelled therefrom at the completion of the working stroke of said piston-hammer.
25. In an impact tool, the combination of a cylinder, a piston-hammer comprising a working piston, a hammer-piston and a rigid connection between said pistons, a cylinder head closing the outer end of said cylinder adjacent said working piston and forming a combustion chamber in said cylinder, a head closing the opposite end of said cylinder adjacent said hammer-piston and forming a compartment in said cylinder between said head and said working piston, one of said compartments being a fuel intake and transfer chamber and the other an air compression chamber, the lengths of said three chambers being substantially equal whereby substantially all of the charge in said fuel intake and transfer chamber is transferred to said explosion chamber on each working stroke of said piston-hammer and substantially all of the air compressed in said air compression chamber is expelled therefrom at the completion of the working stroke of said piston-hammer.

and said hammer-piston, an impact receiving member in said last-mentioned head and adapted to receive the impact of said piston-hammer at the end of the working stroke thereof, and an intermediate cylinder head closing said cylinder between said pistons and forming a compartment in said cylinder between said head and said working piston, one of said compartments being a fuel in-
 10 take and transfer chamber and the other an air compression chamber, the lengths of said three chambers being substantially equal whereby substantially all of the charge in said fuel intake and transfer
 15 chamber is transferred to said explosion chamber on each working stroke of said piston-hammer, whereby substantially all of the air at high pressure is forced out of said air compression chamber by said working
 20 piston in a series of pulsations.

26. In an impact tool, the combination of a cylinder, a piston-hammer reciprocated therein on the principle of an internal combustion engine and including a rotor driven
 25 by said piston-hammer on its working stroke and rotating at a substantially constant speed on an axis coincident with the axis of said cylinder, and means mounted in said cylinder to receive the impact of
 30 said piston-hammer at the end of the working stroke thereof and to transmit said impact to a drill having a through bore, said impact receiving means having a passage therein in registration with the bore in said
 35 drill, and said piston-hammer being also operative on its working stroke to compress air to a high pressure in a portion of said cylinder and to force said air in a rapid succession of pulsations through said passage into
 40 said bore and therethrough to the bottom of the hole being drilled to remove detritus therefrom.

27. In an impact tool, the combination of a cylinder, a piston-hammer reciprocated therein on the principle of an internal combustion engine, a rotor mounted to rotate on an axis substantially coincident with the axis of said cylinder and driven by the piston-hammer at a substantially constant speed
 45 of rotation to effect the return or compression strokes of said piston-hammer said rotor making one complete revolution for every two complete reciprocations of said piston-hammer, and means mounted in said cylinder to receive the impact of said piston-hammer at the end of the working stroke thereof and to transmit said impact to a drill having a through bore, said impact receiving means having a passage therein in registration with
 55 the bore in said drill, said piston being also operative on its working stroke to compress air to a high pressure in a portion of said cylinder and to force said air in a succession of pulsations through said passage and into
 60 said bore and therethrough to the bottom of
 65 said bore and therethrough to the bottom of

the hole being drilled to remove detritus therefrom.

28. In an impact tool, the combination of a cylinder, a piston-hammer reciprocating therein at a constantly increasing speed substantially throughout its forward or working stroke and at a relatively slower speed on its return or compression stroke, said piston-hammer being reciprocated in said cylinder on the principle of an internal combustion engine in so far as the compression, transfer and explosion of the explosive mixture and discharge from the cylinder of the products of combustion are concerned, and an impact receiving means mounted in said cylinder to receive the impact of said piston-hammer as it nears and is substantially at the end of its working stroke, said piston-hammer being also operative to draw air into a portion of said cylinder on its non-working stroke and to compress said air within said portion of said cylinder on its working stroke.

29. In an impact tool, the combination of a cylinder, a piston-hammer reciprocating therein at a constantly increasing speed substantially throughout its forward or working stroke and at a relatively slower speed on its return or compression stroke, said piston-hammer being reciprocated in said cylinder on the principle of an internal combustion engine in so far as the compression, transfer and explosion of the explosive mixture and discharge from the cylinder of the products of combustion are concerned, an impact receiving means mounted in said cylinder to receive the impact of said piston-hammer as it nears and is substantially at the end of its working stroke, said piston-hammer being also operative to draw air into a portion of said cylinder on its non-working stroke and to compress said air within said portion of said cylinder on its working stroke, a drill having an air passage therethrough and having the end of its shank connected to said cylinder, and means to convey the air so compressed in said cylinder to said end of the drill shank, whereby said compressed air is conducted through said drill to the bottom of the hole being drilled to remove detritus therefrom.

30. In an impact tool, the combination of a cylinder provided with a pair of diametrically disposed longitudinally extending slots therethrough, a piston-hammer reciprocated in said cylinder on the principle of an internal combustion engine in so far as the intake, compression, transfer between the compression, explosion and discharge of the products of combustion from the cylinder are concerned, a rotor journaled on said cylinder coaxially therewith and comprising a cam element, a cross-head carried by said piston-hammer having its opposite ends projecting through said slots in said cylinder

and into the path of said cam element, the latter having a plurality of surfaces comprising relatively short steep portions connected to longer portions inclined in less degree and in the opposite direction, the bottoms of said slots being so disposed as to limit the distance which said piston-hammer may move on its forward or working stroke and to prevent said cross-head from engagement with the lowest portion of said cam element.

31. In an impact tool, the combination with a cylinder, a piston-hammer reciprocable therein on the principle of an internal combustion engine, said piston-hammer also cooperating with the cylinder to draw air into a portion of said cylinder during the return or compression stroke of said piston-hammer and to compress air in said cylinder during the power stroke of said piston-hammer, means to regulate and control the pressure of the air so compressed in said cylinder to vary and modify the force of the blow delivered by said piston-hammer, and means to conduct some of the air so compressed from said cylinder on every power stroke of said piston-hammer to the bottom of the hole being drilled to remove detritus therefrom.

32. In an impact tool, the combination of a cylinder, a piston-hammer reciprocable therein on the principle of an internal combustion engine, said piston-hammer cooperating with said cylinder to draw air into a portion of said cylinder during the return stroke of said piston-hammer and to compress air in said cylinder during the power stroke of said piston-hammer, means to regulate and to control the pressure of the air so compressed in said cylinder to vary and modify the force of the blow delivered by said piston-hammer, and means to conduct some of the air so compressed from said cyl-

inder to the combustion end of said cylinder to cool said end of said cylinder. 45

33. In an impact tool, the combination of a cylinder, a piston-hammer reciprocable therein on the principle of an internal combustion engine, said piston-hammer cooperating with said cylinder to draw air into a portion of said cylinder on the return stroke of said piston-hammer and to compress air in said cylinder during the power stroke of said piston-hammer, means to regulate and control the pressure of the air so compressed in said cylinder to vary and modify the force of the blow delivered by said piston-hammer, means to conduct some of the air so compressed to the bottom of the hole being drilled to remove detritus therefrom, and 60 means to conduct some of the air so compressed from said cylinder to the combustion end of said cylinder to cool said end of said cylinder. 55

34. In an impact tool, the combination of a cylinder, a piston-hammer reciprocable therein on the principle of an internal combustion engine, an air filter, said piston-hammer cooperating with said cylinder to draw air through said filter into a portion of said cylinder during the return stroke of said piston-hammer and to compress said air in said cylinder during the power stroke of said piston-hammer, means to regulate and control the pressure of the air so compressed in said cylinder to vary and modify the force of the blow delivered by the piston-hammer, and means to conduct some of the air so compressed and at high pressure on every stroke of said piston-hammer outwardly through 70 said filter to clean the same of any accumulation of dust thereon. 75

In witness whereof, I have hereunto set my hand this twenty-fourth day of August, 1923.

CHARLES STUART SOMERVELL.
